UNITED STATES PATENT OFFICE

GEORGE S. DUNBAR, ALBERT H. NICHOLSON, AND WILLIAM O. BARRY, OF COLUMBUS, OHIO, ASSIGNORS TO THE FEDERAL GLASS COMPANY, OF COLUMBUS, OHIO, A CORPORATION OF OHIO

DESIGN FOR A GLASS PLATE OR ARTICLE OF SIMILAR NATURE

Application filed November 15, 1930. Serial No. 37,680. Term of patent 14 years.

To all whom it may concern:

Be it known that we, GEORGE S. DUNBAR, ALBERT H. NICHOLSON, and WILLIAM O. BARRY, citizens of the United States, residing at Columbus, in the county of Franklin and State of Ohio, have invented a new, original, and ornamental Design for a Glass Plate or Article of Similar Nature, of which the following is the specification, reference being had to the accompanying drawings, forming a part hereof.

We claim:

The ornamental design for a glass plate or article of similar nature, as shown.

GEORGE S. DUNBAR.
ALBERT H. NICHOLSON.
WILLIAM O. BARRY.
